UNITED STATES PATENT OFFICE.

CHARLES F. PRICE, OF RICHMOND HILL, NEW YORK.

DESIGN FOR A DISPLAY SAMPLE-TUBE.

SPECIFICATION forming part of Design No. 34,226, dated March 12, 1901.

Application filed February 6, 1901. Serial No. 46,275. Term of patent 3½ years.

To all whom it may concern:

Be it known that I, CHARLES F. PRICE, a citizen of the United States, and a resident of the city of New York, (Richmond Hill, borough of Queens,) in the county of Queens and State of New York, have invented and produced a new and original Design for a Display Sample-Tube, of which the following is a specification, reference being had to the accompanying drawing, forming a part thereof, in which is represented a side elevation of a display sample-tube embodying the features of my design.

The leading feature of the design consists of a transparent tubular body closed at one end, the opposite end being decorated with a cap which extends some distance along the body.

The detail features of the design consist in the elongated body *a* and the cap *b* at the

upper end of the body, which cap presents at its outer end portions the appearance of a number of protuberances *b'*, giving the cap a milled configuration, and the inner end part of the cap has annular or spiral ribs *b*², presenting the corrugated appearance shown.

Having thus described my invention, I claim as new and desire to secure by Letters Patent—

The design for a display sample-tube herein shown and described.

In testimony whereof I have signed my name to this specification in the presence of two subscribing witnesses.

CHARLES F. PRICE.
